UNITED STATES PATENT OFFICE.

HERVEY S. BITTING, OF LANCASTER, PENNSYLVANIA, ASSIGNOR TO JOSEPH F. BRUEDERLY, OF LANCASTER, PENNSYLVANIA.

SHADE AND CURTAIN-POLE HANGER.

1,141,757.

Specification of Letters Patent. Patented June 1, 1915.

Application filed July 11, 1913, Serial No. 778,613. Renewed April 28, 1915. Serial No. 24,559.

To all whom it may concern:

Be it known that I, HERVEY S. BITTING, a citizen of the United States, residing at Lancaster, in the county of Lancaster and State of Pennsylvania, have invented new and useful Improvements in Shade and Curtain-Pole Hangers, of which the following is a specification.

The present invention relates to shade and curtain pole hangers, and has for its object to provide a construction in which a minimum number of parts are required to furnish proper support for both shade-roller and curtain-pole, and in which but a single fastening is required to secure the fixture in place and permit its ready adjustment; so that defacement of the woodwork to which the fixture is applied by the use of a large number of screws or other securing means is entirely done away with.

In the drawings herewith I have shown one embodiment of my invention, but it will be understood that this embodiment is merely illustrative, and such changes as are within the range of mechanical skill may be made without departing from my invention.

In the drawings:—Figure 1 is a perspective view of a portion of a window casing, showing the fixtures in place. Fig. 2 is a sectional view vertically of the foundation or base-plate, showing the curtain pole supporting arm. Fig. 3 is a view in front elevation of the base-plate, showing the single fastening and adjusting means. Figs. 4, 5, 6, 7 and 8 are detail views showing the mounting of the shade supporting arm. Fig. 9 is a detail view of the curtain pole supporting bracket, looking in the direction of the arrow, Fig. 2.

Referring to the drawings by numerals, like numbers indicating like parts in the several views, 10 indicates the supporting base-plate of the fixture, preferably made of sheet metal, and which, as shown, is of substantially inverted L-shape. The vertical limb of the plate 10 is provided with a securing and adjusting slot 11 through which may be passed a headed screw, preferably a thumb screw, 12, which, when set up in the position shown in Fig. 1, will clamp the plate 10 securely in place. It will be seen that by turning the screw 12 to the position shown in dotted lines in Figs. 2 and 3, at right angles to the position shown in full

lines, the fixture may be readily adjusted for height, and as readily taken off, the slot 11 being of sufficient length and width to permit the plate 10 to be slipped over the head of the screw 12 when slot and head are alined, or to allow for vertical adjustment.

Above and below the slot 11 I provide struck up lugs 13, these lugs being stamped through so as to form apertured seats for the feet of the pole support 14, the said support being of spring metal and in the form of an angle bracket which may be readily sprung into position and removed. Said support 14 has the adjustable member 15 provided with the curved pole seat at one end, its other end passing through an aperture 17 at the angle of the spring bracket which forms the pole-support 14, and having a clamping screw 16 which traverses a slot 18 in the inclined arm of the pole-support for purposes of adjustment.

The horizontal limb 19 of the base-plate 10 is provided with an upset central area 20, in which is formed a slot 21, one side at least of which is notched or serrated, as at 22, to engage the foot 23 of the curtain-supporting bracket 24, which is seated and slides in the upset portion 20 of the horizontal limb 19. The foot 23 of the arm or bracket 24 fits closely within the pocket or way formed by the upset portion, so that it is effectually locked in its adjusted position when the base-plate 10 is clamped flat against the window casing. When adjustment of the curtain bracket is necessary, the base-plate may be loosened, the bracket turned to disengage the edges of the foot 23 from the notches 22, and it may then be shifted to any desired point of adjustment, turned to normal position, and again engaged with a locking notch.

It will be seen that with a fixture of the construction disclosed, but a single plate and a single securing means is necessary to put it up; and, furthermore, adjustment of the fixture as a whole and of the shade bracket may be made merely by loosening the single screw which holds the fixture in place, so that the necessity of drawing from the wood a plurality of fastening means and driving them in new places in the wood-work when the fixture is to be adjusted or removed is wholly unnecessary; and it is obvious that since the base-plate is of a

single piece rigidity of structure and a secure support of all of the parts is insured.

I claim:

1. A fixture of the class described comprising a base-plate having a vertical limb in which is formed a vertical slot and a horizontal limb provided with a horizontal seat, a single fastening means engaging said plate through the vertical slot by which said plate may be adjustably mounted on a window frame, a curtain-pole bracket detachably mounted on said vertical limb, and a shade roller bracket horizontally adjustable and detachably mounted in said seat on said horizontal limb.
2. A fixture of the class described comprising a base-plate of inverted L-shape formed with a vertical slot and a horizontal seat, a single fastening means passing through said slot in the vertical limb of said plate to permit vertical adjustment, bracket engaging seats formed on said vertical limb on either side of said slot, a spring curtain-pole bracket detachably engaging said seats, and a self-locking shade-roller bracket adjustably and detachably mounted in a slot in said seat in the horizontal limb.
3. A fixture of the class described comprising a base-plate of inverted L-shape the vertical limb of which is provided with a longitudinal slot, a single fastening means adapted to turn to engage the slot in said limb when in one position and hold the plate fixed and to be disengaged from the slot when turned into another position, bracket-engaging seats formed on said vertical limb on either side of said slot, a spring curtain-pole bracket detachably engaging said seats, an elongated locking seat having a bracket receiving slot therein on the horizontal limb of said base-plate, a

shade-roller bracket adjustably mounted in said slotted seat and disengageable therefrom upon loosening the base-plate, and automatic locking means for holding said bracket in operative position in said seat.

4. A fixture of the class described comprising a base-plate of inverted L-shape, the vertical limb of which is provided with a longitudinal slot; a thumb screw with an elongated head engaging said slot and serving by said head to secure said base-plate in place when in one position, but disengageable from the base-plate through said slot when in another position; apertured seats formed in the vertical limb of said plate on either side of said slot; a spring curtain-pole bracket having a horizontal leg, an inclined leg and a seat-engaging foot on each leg which resiliently engage said apertured seats; an adjustable pole-seat slidingly mounted in an opening in the projecting angle of said bracket; fastening means to secure said adjustable pole-seat to the inclined slotted leg of said bracket; a recessed slotted seat formed in the horizontal limb of said base-plate; an adjustable shade-roller bracket having an angular foot to engage said slotted seat, 70 said foot adapted to bear against the window casing and maintain the bracket in adjusted position when the base-plate is secured in place, and automatic locking means between said bracket when in operative position and its seat.

In testimony whereof I have hereunto set my hand in presence of two subscribing witnesses.

HERVEY S. BITTING.
